FUEL FEEDING SYSTEM

Arthur C. Allen, Chicago, Ill., assignor to Stewart-Warner Corporation, Chicago, Ill., a corporation of Virginia

Application July 29, 1941, Serial No. 404,540

17 Claims. (Cl. 158—36)

My invention relates to fuel feeding systems and is more particularly concerned with a fuel feeding system wherein pressure obtained from the exhaust of the engine is utilized to feed fuel from the main fuel tank of an automobile to the engine carburetor.

An object of my invention is to provide a new and improved fuel feeding system for automobiles and other forms of machinery.

Another object of my invention is to provide an improved fuel feeding system which maintains a uniform pressure on the fuel for all conditions of engine operation.

Another object of my invention is to provide a fuel feeding system of the class described which will prevent water or water vapor from reaching the fuel tank of the automobile.

Another object of my invention is to provide a fuel feeding system of the class described which will not create an unduly high back pressure on the engine.

Another object of my invention is to provide an improved fuel feeding system of the class described which will operate satisfactorily under all weather conditions.

Another object of my invention is to provide a fuel feeding system of the class described which will not be adversely affected by soot or carbon in the exhaust gases of the engine.

Another object of my invention is to provide a combined muffler and fuel feeding system which will silence the exhaust noises of the engine.

Another object of my invention is to provide a new and improved muffler.

Another object of my invention is to provide a new and improved pressure regulating valve.

Another object of my invention is to provide a new and improved dashpot for controlling the operation of the regulating valve.

Another object of my invention is to provide a new and improved safety valve.

Another object of my invention is to provide a new and improved fuel feeding system which is simple, inexpensive, reliable, and durable and has few moving parts.

Other objects and advantages will become apparent as the description proceeds.

In the drawings:

Figure 1 is a longitudinal sectional view of an automobile embodying my invention;

Figure 2 is a vertical section through the muffler and adjacent parts of the fuel feeding system;

Figure 3 is a view similar to Figure 2, but taken

in a plane at right angles to the plane of Figure 2;

Figure 4 is a vertical section taken on the line 4—4 of Figure 2;

Figure 5 is a vertical section taken on the line 5—5 of Figure 2; and

Figure 6 is a vertical section taken on the line 6—6 of Figure 2.

In Figure 1 of the drawings I have illustrated 10 somewhat diagrammatically, an automobile indicated generally by reference numeral 10, having an internal combustion engine 12 provided with a carburetor 14 supplied with fuel through a conduit 16 from the main fuel tank 18 located 15 at the rear of the automobile. The engine 12 exhausts into a manifold 20 connected by pipe 22 with muffler 24, from whence the exhaust gases are discharged to atmosphere through tail pipe 26. A conduit 28 transmits pressure from the 20 muffler 24 to the fuel tank 18, and this pressure is utilized to force fuel through the conduit 16 to the carburetor 14 in accordance with engine requirements.

Referring particularly to Figures 2 and 3, it will 25 be seen that the muffler 24 comprises a shell 30 formed of sheet metal, or other suitable material, and conformed as clearly shown in these figures. This shell includes a rounded inlet portion 32 provided with an inlet opening 34 adapted to receive one end of the pipe 22. The inlet end of the muffler is illustrated as being provided with an encircling band 36 constituting a clamp for securing the muffler to the pipe 22. A bracket 38 attached to this clamp serves as a means for securing the muffler to an adjacent portion of the 35 automobile frame.

The inlet portion 32 of the muffler shell 30 is illustrated as being attached to the cylindrical portion 40 of this shell by screws 42, or other suitable means. The rear of the muffler shell is formed by a head 44 which may be welded, screwed, or otherwise suitably attached to the cylindrical portion 40.

Exhaust gases entering the muffler from the 45 pipe 22 pass into the inlet tube 46 of a casting 48, the central portion of which is generally cylindrical, as best shown in Figure 3. The casting 48 provides valve seats 50 and 52 for valves 54 and 56, respectively. These valves, as best 50 shown in Figure 4, comprise a casting 58 to which sheet metal valve faces 60 and 62 are suitably secured. The valve faces 60 and 62 are semi-flexible and are preferably made of stainless steel disks providing conical portions for engaging the valve seats 50 and 52.

The upper valve face 50 is secured in place by a retainer 64 press fitted or otherwise suitably secured to the upper end of the valve casting 58. The retainer 64 is cut away, as indicated at 66 to permit flexure of the valve face 50.

The valve face 52 is similarly secured in place by a retainer 68, press fitted or otherwise suitably secured to the lower end of the valve casting 58. This casting 58 is cut away as indicated at 70 to permit flexure of the valve face 52. This particular construction of the valve face reduces noise and rattle, and materially contributes to the quietness of operation of the vehicle.

The valve casting 58 is mounted on a stem 72 attached at its upper end to a dashpot piston 74. This piston 74 is composed of three disks or washers, as clearly shown in Figure 4. The central washer is of smaller diameter than the outside washers, and a pair of piston rings are located in the groove provided by the smaller diameter of the central washer. These washers are preferably made of Monel metal or similar material to reduce corrosion and are retained in place by retainer 76 and lugs 78 broached from the upper end of the stem 72.

The piston 74 reciprocates in a dashpot cylinder 80 carried by a strap 82 screwed to the casting 48, as indicated at 84 and 86. The purpose of the dashpot is to prevent undesirable fluttering of the valves 50 and 52.

In order to protect the dashpot against soot and dirt in the exhaust gases, I surround this dashpot with a sheet metal dome 88 likewise attached to the strap 82. The lower end of this dome 88 is cylindrical and fits loosely over the upper part of the retainer 64 so that the dashpot is surrounded by a relatively dead space containing air or gases substantially free from soot, carbon, or dirt.

The lower end of the stem 72 passes freely through a central opening in a reactor 90. This reactor is preferably formed of sheet metal and is in the form of a frustum of a cone. It is provided with oppositely extending flanges 92 and 94 attached to the lower end of casting 48, as by screws 96 and 100. Beneath the reactor 90 is a guiding strap 98 also secured to the lower end of the casting 48 by screws 96 and 100.

The lower end of the stem 72 is engaged and guided by a plurality of, preferably five, clips 102 attached to the strap 98. These clips are preferably made of a nickel alloy, such as "Inconel," to reduce noise and friction particularly when the stem 72 is covered with carbon or dirt. I have found that this construction is much superior to a solid bushing in that the clips 102 absorb noise and vibration and reduce frictional resistance to operation of the valves.

The casting 48 has an emergency outlet 104 threadedly secured to a tube 106 terminating in an inwardly tapered valve seat 108. An emergency valve 110, preferably formed of sheet metal and having a spherical seat-engaging portion, is normally held in sealing engagement with the seat 108 by a spring 112. One end of the spring surrounds a tubular member 114 constituting a part of the valve 110 and the other end of this spring surrounds a pin 116 attached to the head 44 of the muffler shell.

It will be noted that the plane of the valve seat 108 is vertical and that any water or other liquid which might collect on the valve beyond the valve seat can drop beneath the valve into the space or chamber 118. Any liquid which might collect on that portion of the valve 110 which projects

into the tube 106 can likewise drop or flow into a portion of the tube beneath the valve engaging portion of the conical seat 108. These features are important in that they effectively prevent the emergency valve 110 from being sealed shut by ice formation in cold weather.

In normal operation of my fuel feeding system, the emergency valve 110 remains shut, but if this valve should open, exhaust gases entering the tube 106 would pass through the opening in valve seat 108 and into chamber 118. This chamber is generally oval in vertical section, as best shown in Figures 5 and 6, and surrounds sleeve 120 which, in turn, surrounds the inlet end of the tail pipe 26. Sleeve 120 has an opening 122 formed therein to provide communication between the chamber 118 and the tail pipe 26, whereby exhaust gases passing the emergency valve are discharged through this tail pipe.

When the engine is not operating, the valve 54 rests upon its seat 50 and the valve 56 is substantially in contact with its seat 52. When the parts are cold, the spacing of the valves 54 and 56 is such that there is a clearance of approximately five thousandths of an inch between the valve 56 and its seat 52. This clearance disappears when the parts are hot, but at no time do both valves make air-tight seals with their respective seats.

The exhaust gases entering the cylindrical portion of the casting 48 come in contact with the underside of valve 54 and the upper side of valve 56. Because valve 54 is of larger diameter than valve 56, the valves are raised from their seats and the gases escape into the chamber 124 surrounding the casting 48. The weight of the valve assembly and the difference in effective area between the valves 56 and 52 determine the pressure differential between the interior of the casting 48 and the space 124 surrounding this casting.

Particular attention is directed to the fact that the valves 54 and 56 each present a conical surface to the flow of the exhaust gases past the valves. These conical surfaces cooperate with the respective valve seats to provide gas passages of predetermined size for each position of the valves. When the valves lie closely adjacent their seats, the exhaust gas flows parallel to the conical valve seats and is discharged through the valves in thin cones, one of which is an expanding cone and the other of which is a contracting cone.

When the engine is discharging great quantities of exhaust gases, the pressure in the muffler increases and unless special means were provided the pressure in the casting 48 would likewise increase. The function of the conical reactor 90 is to prevent such increase in pressure in the casting 48. The exhaust gases passing the lower valve 56 strike against the conical reactor 90 and part of these gases are directed upwardly against the lower face of the valve 56 by this reactor. The gases thus directed against the lower face of the valve 56 tend to lift and hold both valves 54 and 56 above their respective seats and thus reduce the differential pressure between the interior of the casting 48 and the space 124 surrounding this casting. The conical shape of the reactor 90 gives the desired lift for the valves 54 and 56 with a minimum of interference with the exhaust gases passing the valve 56.

The gases discharged past the valves 54 and 56 and into space 124 pass through the annular passageway 126 and are discharged through tail pipe 26. The passageway 126 is formed between

the section 40 of the outer shell and a cylindrical inner shell 128. A partition 130 is located at substantially the midpoint of the inner cylindrical shell 128 and cooperates with this shell to form anti-resonant or sound absorbing chambers 132 and 134. In some instances, it is preferable to have the anti-resonant chambers 132 and 134 of different sizes, and this can readily be accomplished by positioning the partition 130 to provide the desired relative sizes of these chambers.

I shall now describe the manner in which the pressure maintained in the casting 48 is transmitted to the fuel tank 18. Referring particularly to Figures 2 and 3, it will be seen that a plug 136 is threaded into a wall of the casting 48 and has a longitudinal bore 138 communicating with the interior of the casting 48. Radial passages 140 connect longitudinal bore 138 with an annular groove 142 in communication with duct 144 in a tubular member 146, having an annular end 148 which surrounds the grooved portion of the plug 136 and is clamped between the head of this plug and the adjacent wall of the casting 48.

The tubular member 146 is secured to one end of a tube 150, the tubular member 146 and tube 150 being inclined upwardly, as best shown in Figure 2. A second and larger tube 152 encloses the right-hand end of the tube 150, the end 154 of tube 152 being bent inwardly and soldered, welded, or otherwise secured to the tube 150 to prevent escape of gases therebetween. The tube 152 is also inclined upwardly but at a lesser angle than the tube 150 so that the extreme right-hand end of the tube 150 is substantially in contact with the upper wall of the tube 152, thereby providing a space 156 into which will flow any water or other liquid which may condense or otherwise collect in the tube 152. The tube 152 extends through the head 44 of the muffler shell, and a short piece of flexible hose 158 of "Neoprene," or other suitable material, connects this tube with the conduit 28. A second hose section 160, which is likewise preferably formed of "Neoprene" or similar material, connects the other end of the conduit 28 with a nipple 162 threaded or otherwise attached to the filling spout 164 adjacent the inlet end thereof and preferably at the highest point of this spout. The inlet end of the spout 164 is closed by a removable cap 166 which is imperforate and which may be provided with a suitable sealing gasket to prevent the escape of air or gas.

The conduit 28 is inclined downwardly from its point of connection with the filling spout 164 to its point of connection with the tube 152. This results in all water condensing in the conduit 28 flowing downwardly in this conduit and into the tube 152 where it eventually accumulates in the space 156 instead of flowing back into the casting 48. This space 156 is inside the muffler shell and is heated by the exhaust gases passing through the muffler. This vaporizes any liquid in the space 156 and the resulting steam passes through tube 158, tubular member 146, and plug 136 into casting 48, whence it mixes with the exhaust gases discharged past the valves 54 and 56 and tail pipe 26.

When the engine is stopped, there is usually sufficient heat remaining in the muffler parts to vaporize any liquid in the space 156. The resulting vapor escapes through tube 158, tubular member 146, plug 136, casting 48, slightly open valve 56, and tail pipe 26 to atmosphere. Any liquid in the space 156 not so vaporized may

evaporate under normal atmospheric conditions, since space 156 is in communication with atmosphere throughout the time the engine is not operating.

5 The tube 152 and conduit 28 are preferably made of relatively large size in order to reduce the rate of flow therethrough so that any water vapor contained in the gases in this tube and conduit will condense and flow downwardly 10 through the conduit and tube to space 156 instead of passing into the fuel tank 18. While I have shown the conduit 28 as connected to the highest point of the filler neck 164, it will be understood that this arrangement is not essential. Where it is inconvenient to connect the conduit 28 to the filler neck, a standpipe may be attached to the fuel tank and the conduit 28 attached to the upper end of the standpipe.

15 My new and improved muffler 24 is preferably 20 protected by a rust proofing process, such as "Metcolizing," which comprises sand blasting, spraying with an aluminum alloy and lacquer, and heat treatment at approximately 1400° F. The spring 112 of the safety valve 110 is preferably 25 made of "Inconel" and is thus not affected by corrosion.

When the automobile engine is not operating, the pressure regulating valves 54 and 56 assume 30 their closed positions. The emergency valve 110 is also closed. As soon as the automobile engine is started, exhaust gases are discharged therefrom through exhaust manifold 20 and pipe 22 into the pressure regulating chamber which constitutes the interior of the casting 48. This inflow of gas into this chamber increases the pressure in this chamber, and also causes a flow 35 through plug 136, tubular member 146, tubes 150 and 152, and conduit 28 to fuel tank 18, producing an increase in pressure in the latter.

40 The flow through the conduit 28 is very slow and any water vapors in the gas there condensed will drain toward the water pocket 156 provided between tubes 150 and 152.

I have found that in the ordinary automobile 45 a pressure of two pounds per square inch above atmospheric pressure is sufficient to force fuel from the tank 18 to the carburetor 14 at a rate sufficient to accommodate the maximum fuel consumption of the engine, and I have, therefore, 50 designed my regulating valves so that they will open when the pressure in the regulating chamber rises to this degree. It will, of course, be understood that these valves can be designed to provide any desired pressure in the fuel tank 18 and that my invention is not limited to a structure which will maintain a two pound pressure in this tank. Those familiar with the art will, of course, appreciate that it is desirable not to maintain a pressure greater than necessary to 55 supply the engine with adequate quantities of fuel, since any excess of pressure produces unnecessary and undesirable back pressure on the automobile engine.

When the pressure in the regulating chamber 60 rises to two pounds above atmospheric pressure, the valves 54 and 56 move upwardly away from their respective seats and the exhaust gases are discharged between these valves and their valve seats. Upward movement of the valves 54 and 56 is accompanied by a corresponding upward movement of the dashpot piston 74, and this piston and the dashpot cylinder cooperate to prevent undesirable fluttering of the regulating valves under the pulsating discharge of engine exhaust.

The valves 54 and 56 cooperate with their respective seats effectively to muffle the sound of the exhaust when the engine is idling or operating at low load. This muffling effect of the valves and their seats is attributable to the pressure and temperature drop of the exhaust gases as they pass the valves and to the further fact that under these conditions of engine operation the gases pass the valves in thin cones whose thickness is less than the length of the sound waves.

The gases discharged past the valves, flow into space 124 and thence through annular passage-way 126 to tail pipe 26 from whence they are discharged to atmosphere. The sound absorbing chambers 132 and 134 are preferably designed to eliminate sound effects from the exhaust gases at higher engine loads where the regulating valves are incapable of completely silencing the engine exhaust.

The gases discharged past the lower valve 56 impinge upon the reactor 90 and some of these gases are redirected against the lower side of the valve 56, thereby tending to lift both valves 54 and 56 from their respective valve seats. This lifting effect is negligible when the engine is idling, or otherwise discharging relatively small volumes of exhaust gases, but as the volume of exhaust gases increases this lifting effect likewise increases and reduces the differential pressure between the regulating chamber and the space 124. This is important in counteracting the effect of the increase in pressure in the space 124 due to back pressure in the muffler shell when the engine is discharging large quantities of exhaust gases. The result is that the pressure in the regulating chamber and likewise in the fuel tank remain at the predetermined value for all conditions of engine operation.

Continued engine operation causes the muffler to heat up and vaporizes any water in the trap 156. The vaporization of this water causes an increased pressure at this point which drives the water vapor through tube 150, tubular member 146, and plug 136 to the regulating chamber whence it mixes with the exhaust gases and is discharged through the tail pipe. This is an important feature of my invention as it prevents any condensation from collecting or remaining on the regulating valves where subsequent freezing of such condensate might cause the regulating valves to stick and render them inoperative, at least temporarily.

The regulating valves 54 and 56, and their associated valve seats, are preferably designed so that little or no liquid can collect at the contact areas between the valves and valve seats, even if some condensation takes place in the pressure regulating chamber. If, however, valves 54 and 56 should fail to open under the predetermined pressure for which they were designed, the pressure in the regulating chamber and emergency exhaust tube 106 will build up until the emergency valve 110 opens. This emergency valve can be set for any desired pressure and I have found that entirely satisfactory results are obtained where this emergency valve is set to open at a pressure approximately one pound greater than the predetermined pressure for which the pressure regulating valves are designed to open and maintain.

As I have previously pointed out, the emergency valve and its seat are designed to prevent the accumulation of water or ice adjacent the contact areas of the valve and valve seat, and tests which I have conducted indicate that it is impos-

sible, or practically so, for this emergency valve to be frozen shut. The continued flow of gases through the emergency valve will result in heating up of the regulating valves and their valve seats, so that any ice which may have collected thereon and temporarily rendered the valves inoperative, will be melted. As soon as this occurs, the regulating valves will resume normal operation and the pressure in the regulating chamber and fuel tank will drop to the predetermined value for which the fuel feeding system is designed to operate. The increased pressure obtaining in the fuel tank while the exhaust is being discharged through the emergency valve will not result in over-supply of fuel to the engine carburetor since the float valve of the carburetor limits the admission of fuel to the float bowl.

When the engine is not operating, the clearance between valve 56 and its seat 52 permits dissipation of the pressure which is maintained in the fuel tank during engine operation. Furthermore, the gases forced into the fuel tank to raise the pressure therein when the engine is started, are composed principally of nitrogen and carbon dioxide, both of which are incapable of chemical reaction with the gasoline. Even when the pressure in the gasoline tank is dissipated, most of the gases remaining therein are nitrogen and carbon dioxide. Both the dissipation of the pressure in the fuel tank when the engine is not operating and the maintenance of predominantly non-inflammable gases therein at all times, materially contribute to the safety of my fuel feeding system.

While I have described and illustrated a preferred embodiment of my invention, it will be understood by those skilled in the art that my invention may be embodied in numerous other forms and that the appended claims are not to be limited to the particular form illustrated and described in detail herein.

I claim:

1. In a fuel feeding system for supplying fuel from a fuel tank to an internal combustion engine having an exhaust pipe, a valve in said pipe biased toward closed position and functioning to maintain a pressure in said pipe when said engine is operating, means beyond said valve acted upon by gases flowing past said valve to cause said gases to tend to open said valve, and means communicating pressure maintained by said valve to said fuel tank to force fuel therefrom to said engine.

2. In a fuel feeding system for an internal combustion engine having an exhaust pipe and supplied with fuel from a fuel tank, the combination of a differential valve for maintaining pressure in said exhaust pipe when said engine is operating, said valve being biased toward closed position, a cone in the path of gases discharged past said valve positioned to redirect said gases against said valve to increase the opening of said valve, whereby the pressure maintained by said valve is uniform for all conditions of engine operation, and means communicating pressure maintained by said valve to said fuel tank to force fuel therefrom to said engine.

3. In a fuel feeding system for an internal combustion engine having an exhaust pipe and supplied with fuel from a fuel tank, the combination of a valve in said exhaust pipe for maintaining fluid pressure therein, a dashpot connected to said valve and preventing undue vibration thereof, means to protect said dashpot from carbon, soot, and dirt in the exhaust gases, and means

communicating pressure maintained by said valve to said fuel tank whereby fuel is forced to said engine.

4. In a fuel feeding system for an internal combustion engine having an exhaust pipe and a fuel tank from which said engine is supplied with fuel, the combination of a valve in said exhaust pipe, said valve comprising a seat, a valve body movable toward and from said seat, a conical semi-resilient face attached to said valve body for flexing movement relative thereto, guide means for said valve body comprising a stem and a plurality of resilient fingers engaging and positioning said stem, and means communicating pressure maintained by said valve to said fuel tank whereby fuel is forced to said engine. 15

5. In a fuel feeding system for an internal combustion engine having an exhaust pipe and supplied with fuel from a fuel tank, a pressure regulating valve in said exhaust pipe for maintaining a predetermined pressure therein, means communicating the pressure maintained by said valve with said fuel tank whereby fuel is supplied therefrom to said engine, and emergency valve means effective upon sticking of said regulating valve to permit the discharge of exhaust gases from said engine.

6. In a fuel feeding system for an internal combustion engine having an exhaust pipe and supplied with fuel from a fuel tank, the combination of a pressure regulating valve in said exhaust pipe, conduit means communicating with said exhaust pipe between said engine and said valve, a filler spout for said fuel tank, means connecting said conduit means with said filler spout at a point above said fuel tank, said conduit means being inclined downwardly from its point of connection to said filler spout to its point of connection with said exhaust pipe, and a water trap in said conduit means for collecting water condensed therein.

7. In a fuel feeding system for an internal combustion engine having an exhaust pipe and supplied with fuel from a fuel tank, the combination of a muffler connected to said exhaust pipe, a pressure regulating chamber in said muffler, a valve in said chamber for maintaining a predetermined minimum pressure therein when said engine is operating, conduit means connecting said pressure regulating chamber with said fuel tank, said conduit means being inclined upwardly from a point adjacent said chamber to a point adjacent said fuel tank, said conduit means having a portion surrounded by said muffler, and a water trap in said portion of the conduit means whereby water condensed in said conduit means will collect in said trap, be vaporized by continued engine operation and will pass into said regulating chamber and be discharged through said valve.

8. In a fuel feeding system for an internal combustion engine having an exhaust pipe and supplied with fuel from a fuel tank, the combination of a pressure regulating chamber communicating with said exhaust pipe, a valve controlling discharge of gases from said chamber and serving to maintain a predetermined pressure therein when said engine is operating, an emergency valve forming a separate outlet for said chamber, said valve having a conical part terminating in a valve seat located in a vertical plane, and a substantially hemispherical valve member cooperating with said seat whereby freezing of said valve is eliminated, and a conduit connecting said pressure regulating chamber with said fuel tank 70

whereby the pressure maintained by said valves is communicated to said fuel tank to force fuel to said engine.

9. In a fuel feeding system for an internal combustion engine having an exhaust pipe and supplied with fuel from a fuel tank, the combination of a muffler connected to said exhaust pipe, said muffler having a shell of sheet metal, a casting located in said shell and providing a pressure regulating chamber, a pressure regulating valve controlling communication between said chamber and the interior of said shell, a cylinder located in said shell and spaced from the walls thereof by inwardly projecting portions of said shell, said shell and cylinder providing an annular passageway for exhaust gases, a partition in said cylinder cooperating therewith to provide a pair of anti-resonant chambers, a tube communicating with said regulating chamber and extending through said anti-resonant chambers, an emergency valve normally closing said tube, a rearward extension on said muffler enclosing said emergency valve and providing a lateral passage for gases discharged therewith, a tail pipe connected to said extension and receiving gases discharged through said annular passageway and past said emergency valve, a tubular stud extending through a wall of said casting, a first tube connecting to said stud and communicating therethrough with said pressure regulating chamber, a second tube telescoped over said first tube, said tubes having parts lying in said anti-resonant chambers and constituting a water trap therein, said tubes being inclined upwardly at different angles, and upwardly inclined conduit means connecting said last-named tube with said fuel tank whereby pressure in said regulating chamber is communicated to said fuel tank and water condensed in said conduit means drains 20 25 30 35 40 into said water trap, is vaporized therein by gases passing through said muffler, and the resulting vapor is discharged through said regulating chamber and past said regulating valve.

10. In a fuel feeding system for an internal combustion engine having an exhaust pipe and supplied with fuel from a fuel tank, the combination of a casting connected to said exhaust pipe and providing a pair of spaced valve seats and a pressure regulating chamber located therebetween, said valve seats being of different diameters, a differential valve having valve faces for engaging said seats, said differential valve being movable toward and from said seats in a vertical direction and being urged toward said seats by its own weight, a valve stem attached to said valve, a dashpot piston attached to the upper end of said valve stem, a dashpot cylinder attached to said casting and receiving said piston, a dirt-excluding enclosure for said dashpot comprising a cover attached to said casting and a portion of said differential valve slidably cooperating with said cover to exclude dirt from said dashpot, a reactance cone surrounding the other end of said valve stem and attached to said casting, a guide member attached to said casting adjacent said cone, resilient fingers carried by said guide member and engaging said stem, and a conduit connecting said pressure regulating chamber with said fuel tank. 45 50 55 60

11. In apparatus of the class described the combination of the main exhaust pipe of an internal combustion engine, a pressure regulating valve for maintaining a pressure in said exhaust pipe when said engine is operating, means for varying the biasing of said valve for different

conditions of engine operation, and means for communicating the pressure maintained by said valve to a point of utilization.

12. In a fuel feeding system for an automobile having a forwardly located internal combustion engine and a rearwardly located fuel supply tank for said engine, the combination of an exhaust pipe for said engine, a valve for maintaining pressure in said exhaust pipe when said engine is operating, a second pipe communicating with said exhaust pipe between said valve and engine, a flexible hose connected to said second pipe, a conduit connected to said hose, an upwardly extending pipe connected to said fuel tank, a second flexible hose connecting said conduit to the upper end of said last-named pipe, a trap associated with said second pipe and adapted to receive liquid condensed in said conduit, and heating means for vaporizing liquid collected in said trap.

13. In apparatus of the class described the combination of an exhaust pipe for an internal combustion engine, a valve in said exhaust pipe, said valve being biased toward closed position to maintain a pressure in said exhaust pipe when the engine is operating, means for utilizing the pressure maintained in said exhaust pipe, a conduit connecting said means with said exhaust pipe intermediate the engine and said valve, and means responsive to an increased flow of exhaust gases past said valve for reducing the differential pressure across said valve.

14. In a fuel feeding system for an engine supplied with combustible fuel contained in a tank, means for forcing gaseous products of combustion into that part of the fuel tank not filled with fuel, and a single means responsive to gas pressure for maintaining said gases compressed during engine operation and for relieving the pres-

sure on said gases when said engine ceases to operate.

15. In a fuel feeding system for an internal combustion engine supplied with fuel from a fuel tank, means for forcing inert exhaust gases of said engine into said fuel tank, means to maintain a predetermined pressure on said gases in said tank during engine operation, and automatic means for relieving the pressure in said fuel tank when said engine ceases to operate.

16. In apparatus of the class described, the combination of an exhaust pipe for an internal combustion engine, a pressure regulating valve for maintaining a predetermined pressure therein, an emergency valve for opening at a higher pressure than said predetermined pressure, said emergency valve being so positioned that gases escaping by way of said emergency valve flow past said pressure regulating valve, whereby heat from said gases will melt any ice interfering with the operation of said pressure regulating valve, and conduit means transmitting the pressure maintained by said pressure regulating valve to means for utilizing said pressure.

17. In a fuel feeding system for an internal combustion engine having an exhaust pipe and supplied with fuel from a fuel tank, the combination of a muffler, a pressure regulating valve in said muffler, a tail pipe connected to said muffler, anti-resonant chambers interposed between said valve and said tail pipe, said valve and anti-resonant chambers cooperating to muffle the exhaust gases discharged by said engine, conduit means communicating pressure maintained by said valve with said fuel tank whereby fuel is supplied to said engine, said conduit means having a part lying in heat exchange relation to said anti-resonant chambers whereby liquid condensed in said means is vaporized.

ARTHUR C. ALLEN.
